DESIGN FOR A TANK BODY FOR VEHICLES

Andrew A. Kramer, Joseph M. Kramer, and Ward M. Gadberry, Kansas City, Mo.; said Gadberry and said Joseph M. Kramer assignors to said Andrew A. Kramer

Application August 24, 1935, Serial No. 58,282

Term of patent 14 years

To all whom it may concern:

Be it known that we, Andrew A. Kramer, Joseph M. Kramer, and Ward M. Gadberry, citizens of the United States, residing at Kansas City, in the county of Jackson and State of Missouri, have invented a new, original, and ornamental Design for a Tank Body for Vehicles, of which the following is a specification, reference being had to the accompanying drawing, forming a part thereof.

Fig. 1 is a perspective view of a tank body showing our new design, and

Fig. 2 is a top plan view thereof on a reduced scale.

We claim:

The ornamental design for a tank body for vehicles substantially as shown.

ANDREW A. KRAMER.
JOSEPH M. KRAMER.
WARD M. GADBERRY.
